UNITED STATES PATENT OFFICE

KENNETH M. WILKINS, OF WAUKEGAN, ILLINOIS, ASSIGNOR TO SUPERIOR TROLLEY SLIDE & EQUIPMENT COMPANY, OF WAUKEGAN, ILLINOIS, A CORPORATION OF ILLINOIS

TROLLEY SLIDE WITH LOCKING MEANS

Application filed January 7, 1932. Serial No. 585,249.

My invention relates generally to current collecting devices and particularly concerns a device which is preferably secured adjacent the end of a trolley pole to collect or obtain current from a trolley wire by a sliding contact.

In current collecting devices of this character the carrier member is generally pivotally connected to a support which in turn is attached to a trolley pole, and said carrier is generally provided with a removable insert or shoe member which is adapted to slidably engage the trolley wire; and one of the principal objects of my invention is to provide a novel arrangement whereby the insert member provides means for locking against displacement the means which provides the pivotal connection between the support and the carrier member.

Another important object of my invention is to construct a device which is provided with means for locking the insert member against displacement with respect to the carrier member.

A further object of my invention is to design and construct a device which is comprised of few parts which may be easily and quickly assembled or disassembled and which may be economically manufactured; and it is also an object to provide a device which forms a compact and durable unit.

Many other objects and advantages of my invention will appear hereinafter in the description when considered in view of the drawing annexed hereto.

With reference to the drawing which discloses one embodiment to which my invention is susceptible—

Fig. 1 is a side view of the device in elevation;

Fig. 2 is a section taken substantially on line 2—2 of Fig. 1;

Fig. 3 is a section taken through a portion of the carrier; and

Fig. 4 is a view showing the means which are employed for pivotally connecting the carrier member to the support.

Considering the principles of construction underlying the particular current collecting device shown, numeral 1 indicates a body

member which provides a support for a carrier member, and as above referred to this body member is preferably secured adjacent the end of a trolley pole and to facilitate a suitable connection, the body member or support is provided with a tubular portion 2 which is provided with an aperture which is adapted to receive the end of a pole. The support, generally designated 1, is formed to provide a bifurcation defined by spaced side walls or arms 3, which in the present instance are preferably integral with the support. The side walls or arms 3 as clearly shown are designed to include bearing portions 4 through which the means extend for pivotally connecting the carrier member to the support. The side walls or arms 3 are made rigid by means of an integral rib portion 5 which extends between the walls. The bearing portions 4 are each provided with an aperture 6 so as to receive a shouldered bushing 7, and said bushings are preferably arranged in the manner shown.

The carrier member generally designated 8 is provided with a base or body portion 9. An aperture 10, transversely arranged, is provided in the body portion of the carrier, and the means which provides a pivotal connection between the carrier and support consists of a pivot 11 which extends through the bearings 4 and aperture 10. The pivot 11 is provided with an under cut slot 12, and an under cut groove 13 corresponding to the shape of the under cut slot 12, is provided in the body portion 9 of the carrier member, and a removable insert member 14 is arranged in the groove 13 and extends through the under cut slot 12 in the pivot 11 and thereby locks the pivot against displacement. It will thus be evident that a novel arrangement of means are employed which provide means for locking the pivotal connection against displacement.

As clearly shown in Fig. 2, the upper part of the carrier member generally designated 8 is formed with upstanding spaced side portions 15 having concave faces or cheeks 15', and the removable insert 14 is provided with a concave groove 16 which conforms more or less to the curvature of the cheek 15'.

portions, all of which provides means for receiving a trolley wire or other conductor.

An aperture 17 is provided adjacent each end of the body portion of the carrier member 8 and as clearly shown, the center of the aperture is arranged or located at a point below the base 18 of the longitudinal under cut groove 13. An aperture 20 is provided adjacent each end of the insert member 14 at the bottom thereof and as clearly shown, the bolts 19 are adapted to extend through said apertures 17 and 20 and when tightened, will provide means for firmly engaging or otherwise securing the insert member against displacement with respect to the carrier. A central longitudinal groove or slot such as 21 is formed in the body portion 9 of the carrier member and obviously facilitates drawing the cheek or side portions 15 of the carrier member towards each other. It will be noted that each end of the carrier member is rounded as at 22, and the removable insert is also rounded as indicated at 23, the provision of which is obvious. An element such as 24 provides an electrical connection between the carrier member and the support therefor.

It will be evident from the forgoing description that I have designed and constructed a device which consists of a carrier member and that improved means are provided for pivotally connecting the carrier member with a support and that a removable insert member is associated with the carrier member and provides means for locking the means providing the pivotal connection against displacement, and it is apparent that means are provided for locking the insert member in position with respect to the carrier member. It will also be evident that the device may be easily and quickly assembled or disassembled, and the several parts are arranged in a compact and durable unit so that an efficient electrical contact between the parts is provided.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the kind described, a carrier member, means provided for connecting said carrier member to a support, and an insert member associated with said carrier member and providing means for locking said connecting means against displacement.

2. In a device of the kind described, a carrier member, means provided for connecting said carrier member to a support, an insert member associated with said carrier member

and providing means for locking said connecting means against displacement, and means provided for locking said insert member against displacement.

3. In a device of the kind described, a support, a carrier member and means connecting same to said support, an insert member associated with said carrier member and providing means for locking the means providing the connection between the carrier and support against displacement. 70

4. In a device of the kind described, a carrier member, means provided for connecting said carrier member to a support, a slot provided in said connecting means and an insert member associated with said carrier member and arranged in said slot to lock said connecting means against displacement. 80

5. In a device of the kind described, a carrier member, means provided for connecting said carrier member to a support, a slot provided in said connecting means, an insert member associated with said carrier member and arranged in said slot to lock said connecting means against displacement, and means provided for locking said insert member in position with respect to said carrier member. 85

6. In a device of the kind described, a support, a carrier member provided with a groove, means providing a connection between said carrier member and said support, a slot provided in said connection, an insert member arranged in said groove and extending through said slot to thereby lock 100 said connection against displacement. 95

7. In a device of the kind described, a support, a carrier member provided with an under cut groove, a pivot providing a connection between said carrier member and said support, a slot provided in said pivot, an insert member arranged in said groove and extending through said slot to thereby lock said pivot against displacement. 105

8. In a device of the kind described, a support, a carrier member provided with a groove, means providing a connection between said carrier member and said support, a slot provided in said connection, an insert member arranged in said groove and extending through said slot to thereby lock said connection against displacement, and means provided for locking said insert member against displacement. 110

9. In a device of the kind described, a forked support, a carrier member provided with a dove tail groove arranged and supported in said fork by means of a slotted pivot, an insert member corresponding to the shape of said groove arranged therein and extending through said slot to lock said pivot against displacement. 120

10. In a device of the kind described, a forked support, a carrier member provided with a dove tail groove arranged and sup- 125

ported in said fork by means of a slotted pivot, an insert member corresponding to the shape of said groove arranged therein and extending through said slot to lock said pivot against displacement, and means provided for locking said insert in said groove.

11. In a device of the kind described, a carrier member, means provided for connecting said carrier member to a support, an insert member associated with said carrier member and providing means for locking said connecting means against displacement, and means extending through said carrier member and engageable with said insert for locking said insert member against displacement.

12. In a device of the kind described, a carrier member, means provided for connecting said carrier member to a support, a slot provided in said connecting means, an insert member associated with said carrier member and arranged in said slot to lock said connecting means against displacement, grooves provided in the underside of said insert member, and means carried by said carrier member and arranged in said grooves for locking said insert member against displacement.

13. In a device of the kind described, a carrier member formed with spaced upstanding side portions, means provided for connecting said carrier member to a support, a slot provided in said connecting means, an insert member arranged between the side portions of said carrier member and arranged in said slot to lock said connecting means against displacement, and means extending through said carrier member and engageable with said insert member for drawing said side portions together in a manner to lock said insert member in a position with respect to said carrier member.

In witness whereof, I hereunto subscribe my name this 16th day of December A. D., 45 1931.

KENNETH M. WILKINS.
